UNITED STATES PATENT OFFICE.

CARL A. ELMSTROM, OF MEDFORD, MASSACHUSETTS.

SHOE-TREE.

Application filed November 26, 1926. Serial No. 150,686.

This invention relates to an expandable shoe tree or stretcher adapted to be put into a shoe to hold it in shape when not being worn or to stretch it for the purpose of changing its shape. I am aware of the fact that many devices for this purpose have been produced.

The principal objects of this invention are to provide a device for this purpose, of simple and inexpensive construction and of such simple character that it can be manipulated by anybody and especially to provide it with means to secure double elongation, that is, expanding it more rapidly than has been the case heretofore, and to provide means whereby when the stretcher is put in position in the shoe, it will itself operate to hold the parts in their stretched condition and yet the operator can easily contract them by releasing the holding device, which requires merely the pushing in of the operating handle.

Other objects and advantages of the invention will appear hereinafter.

Reference is to be had to the accompanying drawings in which

Fig. 1 is a side view of a shoe stretcher constructed in accordance with this invention;

Fig. 2 is a plan of the same with parts in section showing the parts before they are contracted;

Fig. 3 is a similar view with the parts in their fullest expanded position;

Fig. 4 is an end view of the toe part in contracted position with the connecting parts in section on the transverse line 4—4 of Fig. 2;

Fig. 5 is a horizontal section on enlarged scale on the line 5—5 of Fig. 1; and

Fig. 6 is a central transverse sectional view of the parts shown in Fig. 5.

I have shown the invention in a form in which it comprises a heel member 10 of convex shape throughout for fitting into the heel of the shoe. To this is rigidly fixed a rod 11 which is provided with teeth 12 along one side. This constitutes a rack which cooperates with a rack 13 on a rod 14, operated by means, which I will describe later, for the purpose of forcing the two rods 11 and 14 longitudinally apart to expand and contract the device.

The rod 14 is pivoted to a link 15 to which is fixedly secured a wedge 16 which

may be merely a flat plate with a wedge-shaped surface on one side and terminating on the other side in the link 15. These two parts preferably are of integral construction, and formed of sheet metal. The link is provided with a slot or slots 17 through which pass pins 18 driven into a member 19 which constitutes one part of the toe member and projecting into passages in the other part 20 of the toe member. These two toe members together constitute the entire front part of the device and they are divided from each other along a substantially vertical plane. The pins 18 are free to slide in the passages in the toe member 20 and are provided with heads under which are springs 21. These springs are located in enlarged recesses 22, each having a bottom or shoulder. Therefore when the two toe parts are forced apart they separate in a lateral direction, the parts moving in parallel planes. These springs always tend to bring the two parts together into their closed or contracted position. They constitute the only means for closing the toe and the wedge 16 the only means for opening and spreading it.

The two racks 12 and 13 it will be noticed, are provided with simple flat teeth easily made on the surface of the wire rods on which they are located. These teeth are on the sides and these sides are located on the inner sides of the rods so that an operating pinion 25 can engage the two racks on opposite sides and when turned move both racks in opposite directions. This makes it easy to expand and contract the whole device because the heel and toe are forced apart twice as far as has been the custom heretofore for each portion of a turn of the pinion 25. This pinion is mounted on a rod 26 which is provided with a handle 27 fixed thereon for operating it. This pinion is provided with a conical surface in which the teeth of the pinion are cut or otherwise formed. It is located in a similar shaped conical opening through a block 28 in which it is supported and which has passages for the rods 11 and 14. Above this block is a spring 29 bearing on the top of the block and on the bottom of the handle 27.

In operation the user depresses the handle 27 against the opposition of the spring 29 and thus brings the conical pinion 25 down out of intimate contact with the sides

of the conical passage in the block 28 which it normally engages. This leaves the whole rotatable feature of the device free so that it can be turned with no frictional resistance 5 to speak of. When the shoe tree is expanded the operator, of course, will have to let go of the handle and leave it expanded in the position in which it has been. The spring is now free to raise the handle and with it 10 the conical pinion so that the surface of the latter will contact throughout its area with the conical surface of the passage. This supplies friction through the pinion around its teeth and therefore furnishes a considerable resistance against the contraction of the shoe stretcher. This insures that it will remain in its expanded position.

Of course, it will be obvious that when 20 the expansion takes place by the forcing of the link 15 toward the toe the wedge 16 will cooperate with the wedge surface inside the toe piece 19 and force the two parts away from each other as shown in Fig. 3.

This constitutes a simple device for this 25 purpose which will not contract automatically after it has once been expanded and which has no complicated mechanism or features. It is easily and cheaply manufactured and conveniently manipulated by the user. It has all the advantages of the ordinary 30 stretcher and the additional ones above mentioned.

Although I have illustrated and described 35 only a single form of the invention, I am aware of the fact that modifications can be made therein by any person skilled in the art without departing from the scope of the invention as expressed in the claims. Therefore I do not wish to be limited in these 40 respects but what I do claim is:—

1. In a shoe stretcher, the combination with a toe and heel part, of a rod extending from each one toward the other, said rods being connected with both parts and having 45 racks on their faces, a pinion engaging both racks for expanding and contracting the stretcher longitudinally, and means whereby when the stretcher is left in the shoe, friction will be placed automatically on the pinion to prevent contraction of the stretcher.

2. In a shoe stretcher, the combination with a pair of racks, a toe piece and a heel piece connected with the two racks to be operated thereby, of a block having guides for the racks and provided with a conical passage therein, a handle extending into the passage in said block and having teeth upon it for engaging the racks, whereby the turning of the handle will move both racks in opposite directions, the handle having a conical surface on which said teeth are located, whereby when the handle is depressed the toothed portion will be free to turn to operate the racks and can be moved into close 60 engagement with the conical passage to apply 65

a frictional resistance against the turning of the handle.

3. In a shoe tree, the combination with a block having two parallel passages therethrough and a pair of rods extending into the block in opposite directions and having teeth on their sides, said block having a conical passage therethrough between the racks, of a handle having a rod provided with a conical surface fitting said conical passage and having teeth extending therearound and engaging both racks, and a spring for forcing the handle and rod longitudinally to bring the conical surface into frictional engagement with the conical passage when the handle is released. 70 75 80

4. In a shoe tree, the combination with a block having two guides, and a pair of rods extending into the guides in opposite directions and having teeth, said block having a conical passage therethrough between the racks, of a handle provided with a conical surface fitting the conical passage and having teeth extending therearound and engaging both racks, a spring for forcing the handle longitudinally to bring the conical surface into frictional engagement with the passage when the handle is released, a heel portion connected with one of the racks and a toe portion connected with the other, the toe portion comprising two members, one having a slanting surface inside, and a wedge extending into one of said toe members only to engage said slanting surface for forcing them apart. 90 95 100 105

5. In a shoe tree, the combination with a heel portion and a toe portion, the toe portion comprising two members, one having a slanting surface inside and the other an adjacent longitudinal surface, a plurality of transverse guides secured to one and projecting into the other to cause the two members to move toward and from each other by a parallel motion, said guides having springs for normally forcing the two members toward each other, and a wedge extending into one of said toe members only to engage said slanting surface for forcing them apart. 110 115 120

6. In a shoe stretcher, the combination with a pair of racks, a toe piece and a heel piece connected with the two racks to be operated thereby, of a block having a conical passage therein, a handle extending into the passage in said block and having teeth upon it for engaging the racks, the handle having a conical surface, whereby when the handle is depressed the conical portion will be free to turn to operate the racks and can be moved into close engagement with the conical passage to apply a frictional resistance 125 against the turning of the handle.

In testimony whereof I have hereunto affixed my signature.

CARL A. ELMSTROM.
